SWEATER

John Muller, New York, N. Y.

Application October 1, 1954, Serial No. 32,510

Term of patent 14 years

(Cl. D3—4)

Fig. 1.

Fig. 2.

Fig. 1 is a front view of a sweater showing my new design; and

Fig. 2 is an enlarged view of the portion of the sweater shown in the small dot-and-dash circle of Fig. 1.

The dominant feature of my invention lies in the surface configuration of the sweater on the sides of the arm-hole seam, the surface configuration being the same at the front and back of the garment. Said surface configuration consists of a series of individual ornamental units located in echelon on the wales of the body and sleeve, the lines of the echelons being parallel to the seam lines and each individual ornamental unit constituting a pucker, which is elongated in the direction of the wales, and low swellings on both sides of the pucker.

The back of the sweater has the same appearance as the front.

I claim:

The ornamental design for a sweater, substantially as shown and described.
